DESIGN FOR A COMBINED COMB AND CURLER

Herman C. Schlicker, Brooklyn, N. Y., assignor to Rollocurl Corporation, New York, N. Y., a corporation of New York

Application July 22, 1939, Serial No. 86,186

Term of patent 3½ years

To all whom it may concern:

Be it known that I, Herman C. Schlicker, a citizen of the United States of America and a resident of Brooklyn Borough, county of Kings, city and State of New York, have invented a new, original, and ornamental Design for a Combined Comb and Curler, of which the following is a specification, reference being had to the accompanying drawing, forming a part thereof.

In this drawing:

Figures 2 and 3 are end elevational views of the same.

I claim:

The ornamental design for a combined comb and curler, as shown.

HERMAN C. SCHLICKER.
